CAR LADDER

George A. Steuber, Penfield, N. Y., assignor to
Despatch Shops, Inc., a corporation of New
York

Application January 24, 1939, Serial No. 252,697

2 Claims. (Cl. 228—49)

My invention relates to improvements in ladders for railroad cars and has for its object the mounting on a car of a stileless ladder, the rungs of which extend from the side wall of the car around the corner of the car and to the end wall of the car whereby a trainman may mount the rungs on the end of the car and work around to the rungs on the side of the car as there is no obstruction in the rungs from end to end.

10 It is well known to those familiar with railroad practice that trainmen are required to board cars at night when trains are in motion, and are often called upon to perform their duties under adverse weather conditions when such hazards as rain, sleet, ice, snow or intense cold have to be contended with; and it is under these conditions, as well as more favorable conditions, that my improved stileless ladder with unobstructed rungs, one end of which is secured to the side wall of the car and the other end to the end wall of the car, facilitates the movement of the operator in mounting and descending from the car. It will be readily seen by the use of my stileless ladder that there is no corner obstruction for the operator to climb around, and there is no need of an operator releasing his hand from the rungs of the ladder in passing from the side ladder to the end ladder thereby increasing the safety of the operator.

20 30 The specific object of my invention is the provision of the stileless ladder for a car, the rungs of which extend without obstruction continuously from the side wall of the car around the corner of the car to the end wall of the car; and with this and other objects in view my invention consists of the parts and combination of parts hereinafter set forth.

In the drawings:

Figure 1 is a detailed perspective view at one corner of a car with my stileless ladder in position.

Figure 2 is an end view of the car with a stileless ladder in position.

Figure 3 is an enlarged detailed sectional view 45 through the side end and corner wall of a car with my improved ladder in position.

Figure 4 is a top plan view of one of the rungs detached.

Figure 5 is a view similar to Figure 4 showing 50 my improved ladder applied to a square corner car.

The reference numeral 1 designates a car having an end wall 2 and a side wall 3, the corner of the car being rounded as at 3^a, said rounded corner merging into the side and end walls of the

car. While I have shown my invention as applied to a round corner car, it is, of course, understood that it may be applied with equal efficiency to a square cornered car.

The rungs 4 are preferably made from stout bar iron, but, of course, they may be made from any other suitable material. These rungs have spacing arms 5 at each end and attaching ends 6 and 7 which are secured to the car by means of the bolts, or other suitable fasteners 8. The 10 spacing arms 5 are of equal length whereby the rung is spaced an equal distance throughout its length from the walls of the car, as clearly shown in Figure 3, whereby the trainman is assured of an equal foot space between the rung and the 15 walls of the car.

Preferably, I secure to the round corner of the car a spacing member 9 having an eye 10 at one end which is adapted to fit over the rung 4, said spacing member having an end 11 provided 20 with the bolt opening 12 through which the bolt 13 passes to secure the spacer to the round corner wall of the car.

As shown, this spacing member is arranged mainly above the level of the rung and is secured at its upper end to the corner wall and thence inclines or is bent outwardly and downwardly at an angle and secured at its lower end to the rung. By this construction of the rungs and construction and arrangement of the individual supports 9 a trainman in shifting on a rung from side to end or end to side of a car may do so in a safe manner by movements of his feet through a substantially clear space between adjacent rungs and without the necessity 30 of swinging either foot outwardly beyond the plane of the ladder, as he would be compelled to do in the use of a ladder having a center stile or other interfering portions between side and end wall portions of ladder rungs. Also by this construction and arrangement of the rungs the trainman grasping a rung and resting his feet on a lower rung may bring one of his feet to bear on the support 9 of said lower rung to prevent his feet from sliding on the rung and to enable 40 him to brace himself for safer support in inclement weather and against wind pressures, shocks and jars when the train is in motion.

As will be seen from Figure 3, the ladder rungs are permanently bent to conform with the contour of the side end and corner walls of the car.

As will be seen in Figures 1 and 2, these rungs are also mounted on the top of the car and extend integrally and without interruption from the side of the car around to the end of the car.

This stileless ladder embodying my invention is built directly on the car.

While I have herein shown and described what I now consider the proper manner of carrying out my invention, the same is merely illustrative and I contemplate all changes and modifications that may come within the scope of the claims appended hereto.

By the term "no obstruction in the rungs from end to end" I mean that there is no vertical ladder stile over which a train operator must climb in passing from a side ladder to an end ladder. When the operator is holding on to a ladder with one hand and standing on one of the lower rungs the spacing member 9 functions as stated as a protection to brace his foot against slipping and to assist him in maintaining his position on the ladder when the train is in motion.

By means of my improved end and side wall ladder the operator may mount the rungs of the side of the car and work around to the rungs on the end of the car or vice versa.

In the conventional arrangement of freight car ladders the brakeman must step from the side ladder to the end wall ladder because of the distinct separation of the two. Having a separate ladder rung on the side of the car and a separate rung on the end ladder, in instances where they are not on the same plane, the brakeman does not have the safety of my improved integral side and end wall rungs, which maintains the same level at both the side and end wall of the car.

In Figure 5 I have illustrated the application of my stileless ladder to a car having square or rectangular corners. In this view the car is designated by the reference numeral 14. The rungs 15 are of a rectangular shape following the contour of the car corners and have inwardly extending ends corresponding to the ends 5 of the rungs 4 which are secured, respectively, to the side and end walls of the car. The intermediate spacing member 18 is secured at the corner of the car and functions like the spacing member 9.

What I claim is:

1. The combination with a railroad car having an end wall, a side wall and a corner at the junction of said walls, of a stileless ladder consisting solely of a plurality of rungs, spaced an equal distance throughout their length from the end, corner and side walls of the car, one end of each rung having an integral spacing arm secured to the end wall of the car and the other end of each rung having an integral spacing arm secured to the side wall of the car, and an inclined individual support for each rung having an inner end portion secured to the corner wall above the level of the rung and extending outwardly and downwardly at an angle therefrom and having an outer end portion engaging the rung intermediate the ends of the rung, whereby each rung is supported free from connection with any other rung and whereby each individual rung support forms a foot brace against which the foot of a trainman standing on the rung may be brought to bear to assist the trainman in maintaining his position on the ladder when the car is in motion.

2. The combination with a railway car having a side wall, an end wall, and a corner portion connecting said walls, of a stileless ladder consisting solely of a plurality of individual rungs spaced an equal distance throughout their length from the corner portion and side and end walls of the car, one end of each rung being secured to the side wall of the car and the other end thereof to the end wall of the car, and an individual support for each rung located mainly above the level of the rung and having an upper end portion secured to the corner portion of the car and thence bent outwardly and downwardly therefrom and having a lower end engaging the center of the rung, whereby each rung is supported from the car free from connection with any other rung and whereby each individual rung support forms a foot brace against which the foot of a trainman standing on the rung may be brought to bear to assist the trainman in maintaining his position on the ladder when the car is in motion.

GEORGE A. STEUBER.
